UNITED STATES PATENT OFFICE.

CHRISTIAN BERGER, OF BUDAPEST, AUSTRIA-HUNGARY, ASSIGNOR TO SUBMARINE WIRELESS COMPANY, A CORPORATION OF NEW YORK.

CONTROLLING FROM A DISTANT POINT THE OPERATION OF A MECHANISM OR INSTRUMENT.

1,116,870.

Specification of Letters Patent.

Patented Nov. 10, 1914.

Application filed March 19, 1910. Serial No. 550,486.

To all whom it may concern:

Be it known that I, CHRISTIAN BERGER, a subject of the King of Hungary, residing at Budapest, in Austria-Hungary, have invented certain new and useful Improvements in Controlling from a Distant Point the Operation of a Mechanism or Instrument, of which the following is a specification.

10 This invention relates to the controlling from a distant point the operation of a mechanism or instrument.

One of the main objects hereof is to permit the control of a given operation by 15 means of sound waves or similar air pulsations created at a distant point; for example, according hereto one might, by whistling or clapping the hands at one point in a room, cause the operation of a toy or the 20 lighting of a light or similar operation at another part of the room.

Other and more specific objects will appear in the hereinafter following description.

25 According hereto the operation of controlling from a distant point the operation of a mechanism or instrument consists substantially in creating at the distant point the pulsations or sound waves in air, receiving the same at the place of location of the mechanism or instrument by means of a sensitive device such as a microphone which is adapted to change or decrease the normal current in an electrical circuit, causing the 30 current in such circuit to flow through a magnet coil having an armature connected to or forming part of the mechanism or instrument to be controlled, and providing for such armature a force tending to withdraw it from said magnet, such force being inoperative under normal current conditions and insufficient to withdraw the armature, but operative and sufficient to withdraw the armature with the decreased current due to the effect of the air pulsations 45 on the microphone. By "withdrawing the armature" is, of course, meant broadly the separation of the armature and magnet. This movement of the armature can be utilized for various purposes such as closing a 50 second circuit, the current of which performs the desired operation. In another

type of device the relay armature as it is pulled off, directly performs the desired operation mechanically. According to this invention, these devices are useful for operating toys, small lighting devices, igniting devices, house telegraphs and other devices operated by special manipulations, so that the latter device can be operated by a sound action, for instance by a whistle, by clapping the hands, and the like. As such devices are not handled by experts, and as their purchase price does not admit of expensive and careful work 65 and of an accurate adjustment of each single article, another side of the invention relates to improvements in such devices, the object of which is partly to increase the reliability of working, and partly to simplify 70 the said devices.

The apparatus which I prefer for carrying out the present invention comprises the three following elements in a combination: First, a microphone circuit containing a 75 microphone which will be sensitive to sound waves or like pulsations received from the distant point, and the microphone being adapted when affected by pulsations to modify the normal electric current in such 80 circuit. Second, an electro-magnet adapted to have its magnetic pull modified through the modification of current in said circuit. Third, a shiftable part such as an armature, so arranged and fitted as to shift 85 when said magnet is modified from a first position to a second position, the first position being preferably within the operative influence of the magnet and the second position beyond such influence, or in some 90 cases sufficiently within the influence to be returned by the assistance of special expedients. With such apparatus the effect of the sound waves on the microphone is to increase the resistance and cause a fall of current in the circuit so that an electro-magnet in the circuit is weakened, owing to which the armature previously held by the magnet is released so that gravity or a spring may cause the armature's shifting and so that in 95 turn the shifting of the armature may bring about the operation of the mechanism or instrument to be controlled. Sometimes the shifting of the armature will be employed 100

to close a second circuit through which the desired control and operation are effected.

I will first describe and illustrate more or less diagrammatically one or more forms in which the present improvements may be embodied, and will afterward point out in the claims the features of novelty.

In the accompanying drawings, Figure 1 shows diagrammatically the arrangement 10 of a simple form of this invention; Fig. 2 is a diagram illustrating a second form of the invention; and Fig. 3 is a diagram of a third form in which the invention is embodied in a mechanical toy.

In Fig. 1 the circuit of a battery *g* and a device or lamp *x* is closed, on sound waves being produced. This is effected by means of an armature *f* of a magnet *e* connected in series with a microphone *m*, the armature in question adhering in the position of rest to the magnet. Upon the microphone being excited, the armature is relatively separated from the magnet by means of a spring *d* or the like. The current for the toy or other instrument or mechanism is thus closed at the contact *c*. The return of the armature to the magnet is effected manually in this case by means of a press button *r* or the like. The various factors affecting the state 30 of current, namely, battery pressure, microphone resistance, etc., are subject to changes. It is therefore in some cases advisable or essential to use, for disengaging the magnet and armature, a force that would adapt 35 itself to the changing conditions in a better manner than any practically constant spring or other pressure or pull. To that end, in the device diagrammatically shown, in Fig. 2, is arranged a second electro-magnet *v* co- 40 acting in opposition to the first magnet *e*. The second magnet is shown connected in shunt to the microphone *m* on the microphone circuit. The circuits and resistances are so arranged that the current passing 45 through the electro-magnet *v* in the position of rest, is comparatively weak and unable to attract the armature in opposition to the action of the electro-magnet *e* which is powerfully energized by the main circuit. 50 Now in case of sound waves acting on the microphone *m*, the resistance of the microphone increases, whereby the strength of current in the magnet *e*, and therefore the force of attraction of the latter, are decreased, 55 while on the contrary the strength of current in the disengaging electro-magnet *v*, connected in parallel to the microphone, is simultaneously increased in accordance with the changed conditions of resistance, and 60 therefore the attractive force of the latter electro-magnet is also increased. Owing to the differential action of this double change of force, the electro-magnet *v* will now be able to disengage the armature *f* from the magnet *e* and to shift it, and at the same

time the circuit of the device to be operated will be closed by means of the contact *c*. After the sound action has ceased, the original conditions of current will again obtain, so that the device, after the resetting 70 of the armature will again be ready for working. This re-setting can be effected either by hand, for instance, by means of a press button as in Fig. 1, or the distances and arrangements of current and magnets 75 can be so calculated that the magnet *e* will be able to disengage the armature from the electro-magnet *v* and to re-attract and shift it. In either case the original state will be reproduced automatically.

Fig. 3 shows, as a simple example, a construction of device in which the device to be operated, is directly actuated mechanically and not by closing a second circuit. On the side of the box *n* is mounted the microphone 85 *m* in circuit with battery *b* and the magnet *R*, the armature *f* of which is secured to a lever such as the swinging lid of the box, and keeps the latter closed in the position of rest. On the production of the sound action 90 (whistle, clapping of the hands, etc.) the armature, together with the box cover, is released, whereupon the spring *q* throws up the doll *p* or the like, at the same time opening the lid of the box. The armature practically forms a part of and controls the toy mechanism. This device is merely intended to represent an example of the numerous mechanically operated devices which can be constructed in various ways. Thus, for instance, brakes on clockwork can be released, 100 signal disks thrown up, weights allowed to fall, in order to bring about actions of the most varied nature.

It will be seen that by the above described and illustrated embodiments I have accomplished the advantages and objects hereinbefore referred to, and other advantages and functions will be apparent to those acquainted with the subject.

Since many specific features of arrangement, combination and detail shown herein may be varied without departing from the main principles, I do not intend to restrict myself thereto, excepting so far as specified 115 respectively in the appended claims.

What I claim as my invention and desire to secure by Letters Patent is:—

1. In a mechanism having means for actuating it and means for controlling the 120 same from a distant point, the combination of a microphone circuit containing a microphone sensitive to sound waves or like pulsations received from the distant point, said microphone adapted when affected by pulsations to decrease the normal electric current in said circuit, an electro-magnet adapted to have its magnetic pull decreased 125 through the decrease of current in said circuit, a second electro-magnet connected in 130

parallel with said microphone and adapted to have its pull increased when the current in said microphone circuit is decreased, and a shiftable armature adapted to be released 5 from the first magnet and drawn to the second one upon the impact of pulsations on said microphone.

2. Electric acoustic mechanism for operating toys, illuminating devices, igniting 10 devices, house telegraphs, and the like, comprising a source of current, a microphone, a relay magnet, an electrical circuit connecting the source of current to the microphone and the relay magnet, an armature for said 15 relay magnet adhering to the magnet in the state of rest of the microphone, an electrical circuit for operating the device to which the mechanism is attached, a source of current for said circuit, a second magnet 20 adapted to remove the armature from the relay magnet and to close the electrical circuit for operating the device to which the mechanism is attached when the current in the microphone circuit is weakened by 25 sound waves or other mechanical vibrations, and means for energizing said second magnet.

3. Electric acoustic mechanism for operating toys, illuminating devices, igniting 30 devices, house telegraphs, and the like, comprising a source of current, a microphone, a relay magnet, an electrical circuit connecting the source of current to the microphone and the relay magnet, an armature for said 35 relay magnet adhering to the magnet in the state of rest of the microphone, an electrical circuit for operating the device to which the mechanism is attached, a source of current for said circuit, a second magnet 40 adapted to remove the armature from the relay magnet and to close the electrical circuit for operating the device to which the mechanism is attached when the current in the microphone circuit is weakened by 45 sound waves or other mechanical vibrations and a circuit including said second magnet and connected in parallel with the microphone circuit.

4. Apparatus controllable by sound waves 50 from a distant point comprising, in combination, a microphone circuit containing a microphone sensitive to sound waves or like pulsations received from the distant point, said microphone adapted when affected by 55 such pulsations to modify the normal electric current in said circuit, an electro-magnet adapted to have its magnetic pull modified through the modification of current in said circuit, a shiftable armature arranged 60 in coöperative relation with said magnet, and means for producing an automatically variable counterforce tending to relatively 65 separate said magnet and armature.

5. Apparatus controllable by sound waves 65 from a distant point comprising, in combi-

nation, a microphone circuit, containing a microphone sensitive to sound waves or like pulsations received from the distant point, said microphone adapted when affected by such pulsations to modify the normal electric current in said circuit, an electro-magnet adapted to have its magnetic pull modified through the modification of current in said circuit, a shiftable armature arranged in coöperative relation with said magnet, 70 and means for producing an automatically variable counterforce tending to relatively separate said magnet and armature comprising a second electro-magnet connected up to increase in strength when the first 75 magnet decreases.

6. Apparatus controllable by sound waves from a distant point comprising, in combination, a microphone circuit containing a microphone sensitive to sound waves or like 80 pulsations received from the distant point, said microphone adapted when affected by such pulsations to modify the normal electric current in said circuit, an electro-magnet adapted to have its magnetic pull modified through the modification of current in 85 said circuit, a shiftable armature arranged in coöperative relation with said magnet, and means for producing an automatically variable counterforce tending to relatively 90 separate said magnet and armature comprising a second electro-magnet connected up in parallel with said microphone, whereby increased resistance in the microphone decreases the current in the first and increases it in the second magnet.

7. Apparatus controllable by sound waves from a distant point comprising, in combination, a microphone circuit containing a microphone sensitive to sound waves or like 100 pulsations received from the distant point, said microphone adapted when affected by such pulsations to modify the normal electric current in said circuit, a magnet coil adapted to have its magnetic pull modified through the modification of current in said circuit, a shiftable armature arranged to be normally drawn toward such coil, a second magnet coil arranged to offset the effect of 105 the first coil, and means for causing the 110 strength of the second coil to increase when the first decreases.

8. Apparatus controllable by sound waves from a distant point comprising, in combination, a microphone circuit containing a microphone sensitive to sound waves or like 120 pulsations received from the distant point, said microphone adapted when affected by such pulsations to modify the normal electric current in said circuit, a magnet coil adapted to have its magnetic pull modified through the modification of current in said circuit, a shiftable armature arranged to be normally drawn toward such coil, a second magnet coil arranged to offset the effect of 125 130

the first coil, and means for causing the strength of the second coil to increase when the first decreases, comprising a shunt circuit for the second coil, whereby increased 5 resistance at the microphone decreases the current in the first and increases it in the second coil.

In testimony whereof I have signed my name to this specification in the presence of two subscribing witnesses.

CHRISTIAN BERGER.
